US0D1017649S

(12) **United States Design Patent** (10) **Patent No.:** **US D1,017,649 S**
(45) **Date of Patent:** **** Mar. 12, 2024**

(54) **CHILLER UNIT**

(71) Applicant: **Mitsubishi Electric Corporation**,
Tokyo (JP)

(72) Inventors: **Takuya Ito**, Tokyo (JP); **Junichi Miyai**,
Tokyo (JP); **Yuji Tarumi**, Tokyo (JP);
Kazuki Murakawa, Tokyo (JP);
Kimitaka Kadowaki, Tokyo (JP);
Yoshio Yamano, Tokyo (JP); **Tomoya Kimura**, Tokyo (JP)

(73) Assignee: **Mitsubishi Electric Corporation**,
Tokyo (JP)

(**) Term: **15 Years**

(21) Appl. No.: **29/791,959**

(22) Filed: **Feb. 22, 2022**

(30) **Foreign Application Priority Data**

Aug. 30, 2021 (JP) ..... 2021-018639 D

(57) **CLAIM**

The ornamental design for a chiller unit, as shown and described.

DESCRIPTION

FIG. 1. is a perspective view of a chiller unit showing our new design;

FIG. 2. is a front view thereof;

FIG. 3. is a rear view thereof;

FIG. 4. is a left side view thereof;

FIG. 5. is a right side view thereof;

FIG. 6. is a top plan view thereof; and,

FIG. 7. is a bottom view thereof.

The broken lines depict portions of the chiller unit that form no part of the claimed design.

1 Claim, 7 Drawing Sheets
